STATIC CHARGE ELIMINATOR AND
STATIC CHARGE ELIMINATION METHOD

TECHNICAL FIELD

The present invention relates to a static charge eliminator and a static charge elimination method.

BACKGROUND ART

A self-discharge type static charge eliminator is disclosed in Japanese Patent No. 4251762 (PTL 1).

CITATION LIST

Patent Literature

PTL 1: Japanese Patent No. 4251762

SUMMARY OF INVENTION

Technical Problem

However, when the absolute value of the surface potential of an insulating film to be neutralized is low, the self discharge may not occur between the insulating film and the static charge eliminator, and thereby, it is impossible to use the self-discharge type static charge eliminator to eliminate the static charges on the insulating film. The present invention has been made in view of the problem mentioned above, and it is an object of the present invention to provide a self-discharge type static charge eliminator and a static charge elimination method capable of reliably eliminating the static charges on the insulating film.

Solution to Problem

The static charge eliminator of the present invention includes a charger including at least one charging unit, and a grounded needle-shaped conductor. The charger is configured to charge an insulating film by contacting the insulating film such that the absolute value of the surface potential of the insulating film is 3 kV or more. The needle-shaped conductor is arranged to generate a corona discharge between the insulating film charged by the charger and the needle-shaped conductor.

The static charge elimination method of the present invention includes charging an insulating film by bringing a charger into contact with a surface of the insulating film such that the absolute value of the surface potential of the insulating film is 3 kV or more, and generating a corona discharge between a grounded needle-shaped conductor and the charged insulating film.

Advantageous Effects of Invention

In the static charge eliminator of the present invention, the charger is configured to charge an insulating film by contacting the insulating film such that the absolute value of the surface potential of the insulating film is 3 kV or more. Therefore, it is possible to reliably generate a corona discharge between the grounded needle-shaped conductor and the insulating film. According to the static charge eliminator of the present invention, the static charges on the insulating film can be reliably eliminated.

In the static charge elimination method of the present invention, the insulating film is charged by bringing the

2

charger into contact with a surface of the insulating film such that the absolute value of the surface potential of the insulating film is 3 kV or more. Therefore, it is possible to reliably generate a corona discharge between the grounded needle-shaped conductor and the insulating film. According to the static charge elimination method of the present invention, the static charges on the insulating film can be reliably eliminated.

10 BRIEF DESCRIPTION OF DRAWINGS

FIG. 1 is a schematic view illustrating a static charge eliminator according to a first embodiment of the present invention;

15 FIG. 2 is an enlarged schematic view illustrating a part of the static charge eliminator according to the first embodiment of the present invention;

20 FIG. 3 is an enlarged schematic view illustrating a part of the static charge eliminator according to the first embodiment of the present invention;

FIG. 4 is a schematic view illustrating a static charge eliminator according to a modification of the first embodiment of the present invention;

25 FIG. 5 is a flowchart illustrating a static charge elimination method according to the first embodiment of the present invention;

FIG. 6 is a schematic view illustrating a static charge eliminator according to a second embodiment of the present invention;

30 FIG. 7 is a schematic view illustrating a static charge eliminator according to a third embodiment of the present invention;

FIG. 8 is a block diagram illustrating an exemplar configuration of a controller included in the static charge eliminator according to the third embodiment of the present invention;

35 FIG. 9 is a schematic view illustrating a static charge eliminator according to a fourth embodiment of the present invention; and

40 FIG. 10 is a schematic view illustrating a static charge eliminator according to a fifth embodiment of the present invention.

DESCRIPTION OF EMBODIMENTS

45 Embodiments of the present invention will be described hereinafter. The same components will be denoted by the same reference numerals, and the description thereof will not be repeated.

50 First Embodiment

A static charge eliminator 1 according to a first embodiment will be described with reference to FIGS. 1 to 3. The 55 static charge eliminator 1 of the present embodiment includes a charger 20 and a grounded needle-shaped conductor 30. The static charge eliminator 1 of the present embodiment may further include a bobbin 10 around which the insulating film 11 is wound.

60 The insulating film 11 has a first surface 12 and a second surface 13 opposite to the first surface 12. The insulating film 11 is not particularly limited, it may be a plastic film such as a polyethylene terephthalate (PET) film, a polyester film, a polyethylene film, a polypropylene film, a polyvinyl chloride film, a polyimide film, a nylon film, or it may be a piece of paper. The insulating film 11 is wound around the bobbin 10, and may be stored as a film roll. Although not

particularly limited, the bobbin 10 may be made of an insulating material such as paper or resin, or a conductive material such as metal.

The absolute value of the surface potential of the insulating film 11 before being conveyed to the charger 20 is less than 3 kV. The absolute value of the surface potential of the insulating film 11 before being conveyed to the charger 20 may be, for example, 2 kV or more and less than 3 kV. In the present specification, the surface potential of the insulating film 11 is defined as a potential caused by the first charges on the first surface 12 and the second charges on the second surface 13. When the insulating film 11 is unwound from the bobbin 10, the insulating film 11 is peeled off from the adjacent insulating film 11 or rubs against the adjacent insulating film 11 or is peeled off from the adjacent insulating film 11 while rubbing against the adjacent insulating film 11. Thus, for example, the first charges having a first polarity (for example, a negative polarity) are formed on the first surface 12, and the second charges having a second polarity (for example, a positive polarity) opposite to the first polarity are formed on the second surface 13. The amount of the second charges is substantially equal to the amount of the first charges. Therefore, the absolute value of the surface potential of the insulating film 11 before being conveyed to the charger 20 is small.

The charger 20 is disposed downstream of the bobbin 10 in the conveying direction of the insulating film 11. The insulating film 11 is conveyed to the charger 20. The charger 20 includes one or more charging units (21, 22). The charger 20 may include a plurality of charging units (21, 22). One or more charging units (21, 22) are configured to charge the insulating film 11. At least one (for example, a first charging unit 21) of the plurality of charging units (21, 22, 23) may be arranged to face one surface (for example, the first surface 12), and the rest (for example, a second charging unit 22, a third charging unit 23) of the plurality of charging units (21, 22, 23) may be arranged to face the other surface (for example, the second surface 13).

In the static charge eliminator 1 of the present embodiment, the charger 20 includes two charging units (a first charging unit 21 and a second charging unit 22). The first charging unit 21 is arranged to face the first surface 12 of the insulating film 11, and the second charging unit 22 is arranged to face the second surface 13 of the insulating film 11. As illustrated in FIG. 4, in a static charge eliminator 1b according to a modification of the present embodiment, the charger 20 may include three charging units (a first charging unit 21, a second charging unit 22, and a third charging unit 23). The first charging unit 21 is arranged to face the first surface 12 of the insulating film 11, and the second charging unit 22 and the third charging unit 23 are arranged to face the second surface 13 of the insulating film 11.

Each of one or more charging units (21, 22, 23) includes an insulating member 21a, 22a, 23a. Each insulating member 21a, 22a, 23a is configured to contact a surface (at least one of the first surface 12 and the second surface 13) of the insulating film 11. The insulating members 21a, 22a, 23a may be made of the same material. The insulating member (for example, the insulating member 21a) included in at least one (for example, the first charging unit 21) of the plurality of charging units (21, 22, 23) may be made of a different material from the insulating member (for example, the insulating member 22a, the insulating member 23a) included in the rest (for example, the second charging unit 22, the third charging unit 23) of the plurality of charging units (21, 22, 23).

The insulating members 21a, 22a, 23a are made of a material having a different level in the triboelectric series from the insulating film 11. For example, the insulating members 21a, 22a, 23a may be made of a material having a higher level in the triboelectric series than the insulating film 11. Specifically, the insulating film 11 may be made of a material having a relatively lower level in the triboelectric series, and the insulating members 21a, 22a, 23a may be made of a material having a relatively higher level in the triboelectric series. As an example, the insulating film 11 may be made of polyethylene terephthalate (PET), and the insulating members 21a, 22a, 23a may be made of glass or silicone rubber. When a material has a relatively lower level in the triboelectric series, it means that the material is relatively easy to be negatively charged, and when a material has a relatively higher level in the triboelectric series, it means that the material is relatively easy to be positively charged. As illustrated in FIGS. 2 and 3, when the insulating members 21a, 22a, and 23a are made of a material having a higher level in the triboelectric series than the insulating film 11, both surfaces (the first surface 12 and the second surface 13) of the insulating film 11 are negatively charged by one or more charging units (21, 22, 23).

For example, the insulating members 21a, 22a, 23a may be made of a material having a lower level in the triboelectric series than the insulating film 11. Specifically, the insulating film 11 may be made of a material having a relatively higher level in the triboelectric series, and the insulating members 21a, 22a, 23a may be made of a material having a relatively lower level in the triboelectric series. As an example, the insulating film 11 may be made of nylon, and the insulating members 21a, 22a, 23a may be made of natural rubber or vinyl chloride. As another example, the insulating film 11 may be made of paper, and the insulating members 21a, 22a, 23a may be made of Teflon (registered trademark). When the insulating members 21a, 22a, 23a are made of a material having a lower level in the triboelectric series than the insulating film 11, both surfaces (first surface 12 and second surface 13) are positively charged by one or more charging units (21, 22, 23).

Each of the one or more charging units (21, 22, 23) includes a roller 21b, 22b, 23b covered by the insulating member 21a, 22a, 23a. The rollers 21b, 22b, 23b may have the same diameter. At least two of the rollers 21b, 22b, 23b may have a diameter different from each other. When the insulating film 11 is being conveyed, the rollers 21b, 22b, 23b covered by the insulating members 21a, 22a, 23a are made to rotate in such a manner that the insulating members 21a, 22a, 23a are brought into contact with a surface (at least one of the first surface 12 and the second surface 13) of the insulating film 11. Alternatively, when the insulating film 11 is being conveyed, the rollers 21b, 22b, 23b covered by the insulating members 21a, 22a, 23a may be made to rotate in such a manner that the insulating members 21a, 22a, 23a are brought into contact with both surfaces (the surface 12 and the second surface 13) of the insulating film 11. Specifically, when the insulating film 11 is being conveyed, the rollers 21b, 22b, 23b covered by the insulating members 21a, 22a, 23a may be made to rotate in such a manner that the insulating member 21a is brought into contact with the first surface 12 of the insulating film 11 and the insulating members 22a and 23a are brought into contact with the second surface 13 of the insulating film 11.

The rollers 21b, 22b, 23b may be conductive. The rollers 21b, 22b, 23b may be made of a metal material such as stainless steel or aluminum. The rollers 21b, 22b, 23b may be grounded. After the insulating members 21a, 22a, 23a are

brought into contact with the insulating film 11, the insulating members 21a, 22a, 23a are peeled off from the insulating film 11, or rub against the insulating film 11, or are peeled from the insulating film 11 while rubbing against the insulating film 11. Therefore, after the insulating film 11 is conveyed to pass through each of the one or more charging units (21, 22, 23), the insulating members 21a, 22a, 23a are charged with static charges having a polarity opposite to that of the insulating film 11. At least a part of the static charges accumulated in the insulating members 21a, 22a, 23a can be eliminated by the grounded rollers 21b, 22b, 23b.

The charger 20 is configured to charge the insulating film 11 such that the absolute value of the surface potential of the insulating film 11 is 3 kV or more. For example, it is possible for the charger 20 to charge the insulating film 11 such that the absolute value of the surface potential of the insulating film 11 is 3 kV or more by appropriately setting the material of the insulating film 11, the materials of the insulating members 21a, 22a, 23a, the contact pressure between the insulating film 11 and the insulating members 21a, 22a and 23a, the contact length between the insulating film 11 and the insulating members 21a, 22a and 23a, and the number of one or more charging units (21, 22, 23) included in the charger 20.

The charger 20 may be configured to charge the insulating film 11 such that the absolute value of the surface potential of the insulating film 11 is 30 kV or less. The charger 20 may be configured to charge the insulating film 11 such that the absolute value of the surface potential of the insulating film 11 is 20 kV or less. For example, it is possible for the charger 20 to charge the insulating film 11 such that the absolute value of the surface potential of the insulating film 11 is 30 kV or less or 20 kV or less by appropriately setting the material of the insulating film 11, the materials of the insulating members 21a, 22a, 23a, the contact pressure between the insulating film 11 and the insulating members 21a, 22a and 23a, the contact length between the insulating film 11 and the insulating members 21a, 22a and 23a, and the number of one or more charging units (21, 22, 23) included in the charger 20.

In one example, the insulating film 11 is made of polyethylene terephthalate (PET), and the insulating members 21a, 22a, 23a are made of glass. In this example, the absolute value of the surface potential of the insulating film 11 charged by the charger 20 is 18 kV to 20 kV.

The needle-shaped conductor 30 is disposed downstream of the charger 20 in the conveying direction of the insulating film 11. The needle-shaped conductor 30 is a conductor having a tip 31 facing the insulating film 11. The needle-shaped conductor 30 may include one tip 31 or a plurality of tips 31. The needle-shaped conductor 30 is not particularly limited, it may be a conductive cord or a conductive brush. The needle-shaped conductor 30 is not particularly limited, it may include a conductive material such as stainless steel, copper, brass, aluminum or titanium.

The needle-shaped conductor 30 is grounded. The needle-shaped conductor 30 is arranged to generate a corona discharge between the insulating film 11 charged by the charger 20 and the needle-shaped conductor 30. A gap g between the needle-shaped conductor 30 and the insulating film 11 may be 5 cm or less or may be 2 cm or less, for example. The corona discharge is generated by the potential difference between the insulating film 11 charged by the charger 20 and the needle-shaped conductor 30. The grounded needle-shaped conductor 30 constitutes a self-discharge type static charge eliminator.

The corona discharge generates ions in the vicinity of the first surface 12 and the second surface 13 of the insulating film 11 near the needle-shaped conductor 30 by ionizing air around the needle-shaped conductor 30. Among the generated ions, those ions having a polarity opposite to the polarity of the static charges on both surfaces (the first surface 12 and the second surface 13) of the insulating film 11 after passing through the charger 20 are attracted to both surfaces (the first surface 12 and the second surface 13) of the insulating film 11. Thus, the static charges on both surfaces (the first surface 12 and the second surface 13) of the insulating film 11 are neutralized by those ions, and thereby, the static charges on the insulating film 11 are eliminated.

A static charge elimination method according to the first embodiment and its modification will be described with reference to FIG. 5. The static charge elimination method of the present embodiment includes charging the insulating film 11 such that the absolute value of the surface potential of the insulating film 11 is 3 kV or more (S1). Charging the insulating film 11 (S1) may include bringing the insulating members 21a, 22a, 23a into contact with a surface (at least one of the first surface 12 and the second surface 13) of the insulating film 11. The static charge elimination method of the present embodiment further includes generating a corona discharge between the grounded needle-shaped conductor 30 and the charged insulating film 11 (S2).

The effects of the static charge eliminator 1, 1b and the static charge elimination method of the present embodiment and its modification will be described.

The static charge eliminator 1, 1b according to the present embodiment and its modification includes a charger 20 including at least one charging unit (21, 22, 23) and a grounded needle-shaped conductor 30. The charger 20 is configured to charge the insulating film 11 by contacting the insulating film 11 such that the absolute value of the surface potential of the insulating film 11 is 3 kV or more. The needle-shaped conductor 30 is arranged to generate a corona discharge between the insulating film 11 charged by the charger 20 and the needle-shaped conductor 30.

The charger 20 charges the insulating film 11 by contacting the insulating film 11 such that the absolute value of the surface potential of the insulating film 11 is 3 kV or more. Therefore, it is possible to reliably generate a corona discharge between the grounded needle-shaped conductor 30 and the insulating film 11. According to the static charge eliminator 1, 1b of the present embodiment and its modification, the static charges on the insulating film 11 can be reliably eliminated.

Usually, when a power supply is required in an environment with explosion-proof requirements, the required power supply should be explosion proof, which makes it large in size. However, in the static charge eliminator 1 or 1b of the present embodiment, the static charges on the insulating film 11 may be eliminated without using a power supply. Thus, the static charge eliminator 1 or 1b of the present embodiment can be easily introduced into such an environment at a low cost. Further, in the static charge eliminator 1, 1b of the present embodiment and its modification, no power supply is needed for delivering the insulating film 11. Therefore, there is no limitation on the delivering speed of the insulating film 11 due to the power supply, and the delivering speed of the insulating film 11 can be set freely.

According to the static charge eliminator 1, 1b of the present embodiment and its modification, the static charges on the insulating film 11 can be reliably eliminated, which make it possible to prevent foreign matters present in the

circumstance of the insulating film 11 (for example, in the air around the insulating film 11) from being adhered to the insulating film 11 by the static charges. From the viewpoint of preventing the adhesion of foreign matters to the insulating film 11, there is no need to completely eliminate the static charges on the insulating film 11, and the static charges on the insulating film 11 should be eliminated to such an extent that foreign matters will not be adhered to the insulating film 11 by the static charges.

In the static charge eliminator 1, 1b of the present embodiment and its modification, the grounded needle-shaped conductor 30 is arranged in such a manner that a corona discharge may be generated between the needle-shaped conductor 30 and the insulating film 11. The grounded needle-shaped conductor 30 constitutes a self-discharge type static charge eliminator. According to the static charge eliminator 1, 1b of the present embodiment and its modification, the corona discharge may be generated between the needle-shaped conductor 30 and the insulating film 11 without applying a high voltage to the needle-shaped conductor 30. Therefore, the static charge eliminator 1, 1b according to the present embodiment and its modification may be used without any additional equipments in a working environment (such as a process of manufacturing a coil which includes a step of covering a conductor with the insulating film 11) which is required to prevent sparks from occurring.

In the static charge eliminator 1, 1b of the present embodiment and its modifications, one or more charging units (21, 22, 23) each include a roller 21b, 22b, 23b covered by the insulating member 21a, 22a, 23a having a different level in the triboelectric series from the insulating film 11. The insulating member 21a, 22a, 23a may be configured to contact a surface (at least one of the first surface 12 and the second surface 13) of the insulating film 11. According to the static charge eliminator 1, 1b of the present embodiment and its modification, the insulating film 11 may be charged to such an extent that a corona discharge may be reliably generated between the grounded needle-shaped conductor 30 and the insulating film 11 simply by bringing the insulating member 21a, 22a, 23a into contact with a surface (at least one of the first surface 12 and the second surface 13) of the insulating film 11.

In the static charge eliminator 1, 1b of the present embodiment and its modification, one or more charging units (21, 22, 23) may be a plurality of charging units (21, 22, 23). The amount of static charges on the insulating film 11 may be increased by using the plurality of charging units (21, 22, 23) to charge a surface (at least one of the first surface 12 and the second surface 13) of the insulating film 11. The charger 20 may charge the insulating film 11 such that the absolute value of the surface potential of the insulating film 11 is surely 3 kV or more.

In the static charge eliminator 1, 1b of the present embodiment and its modification, the surface of the insulating film 11 includes one surface (for example, the first surface 12) of the insulating film 11 and the other surface (for example, the second surface 13) opposite to the one surface (for example, the first surface 12). At least one (for example, the first charging unit 21) of the plurality of charging units (21, 22, 23) may face the one surface (for example, the first surface 12), and the rest (for example, the second charging unit 22, the third charging unit 23) of the plurality of charging units (21, 22, 23) may face the other surface (for example, the second surface 13). According to the static charge eliminator 1, 1b of the present embodiment and its modification, the static charges on both surfaces (the

first surface 12 and the second surface 13) of the insulating film 11 can be reliably eliminated.

In the static charge eliminator 1, 1b of the present embodiment and its modification, the insulating member 5 (for example, the insulating member 21a) included in at least one (for example, the first charging unit 21) of the plurality of charging units (21, 22, 23) may be made of a different material from the insulating member (for example, the insulating member 22a, the insulating member 23a) included in the rest (for example, the second charging unit 22, the third charging unit 23) of the plurality of charging units (21, 22, 23). Thus, even though both surfaces (the first surface 12 and the second surface 13) of the insulating film 11 are made of different materials from each other, it is possible to charge the insulating film 11 such that the absolute value of the surface potential of the insulating film 11 is surely 3 kV or more.

For example, the first surface 12 of the insulating film 11 20 may be charged by bringing the insulating member (for example, the insulating member 21a) included in at least one (for example, the first charging unit 21) of the plurality of charging units (21, 22, 23) into contact with the first surface 12 of the insulating film 11, and the second surface 13 of the insulating film 11 may be charged by bringing the insulating member (for example, the insulating member 22a, the insulating member 23a) included in the rest (for example, the second charging unit 22, the third charging unit 23) of the plurality of charging units (21, 22, 23) into contact with the second surface 13 of the insulating film 11. Thus, even though both surfaces (the first surface 12 and the second surface 13) of the insulating film 11 are made of different materials from each other, it is possible to charge the insulating film 11 such that the absolute value of the surface potential of the insulating film 11 is surely 3 kV or more. According to the static charge eliminator 1, 1b of the present embodiment and its modification, the static charges on both surfaces (the first surface 12 and the second surface 13) of the insulating film 11 can be reliably eliminated.

40 In the static charge eliminator 1, 1b of the present embodiment and its modification, one or more charging units (21, 22, 23) each may include a roller 21b, 22b, 22c covered by the insulating member 21a, 22a, 23b. According to the static charge eliminator 1, 1b of the present embodiment and its modification, since the insulating film 11 can be charged while being conveyed, the static charges on the insulating film 11 can be eliminated efficiently.

45 In the static charge eliminator 1 or 1b of the present embodiment and its modification, the charger 20 may be configured to charge the insulating film 11 such that the absolute value of the surface potential of the insulating film 11 is 30 kV or less. Therefore, it is possible to prevent the insulating film 11 from being imparted with excessive static charges by the charger 20. According to the static charge 50 eliminator 1, 1b of the present embodiment and its modification, the static charges imparted to the insulating film 11 by the charger 20 may be eliminated in a short time by the grounded needle-shaped conductor 30.

The static charge elimination method of the present embodiment and its modification includes charging the insulating film 11 by bringing the charger 20 into contact with a surface (at least one of the first surface 12 and the second surface 13) of the insulating film 11 such that the absolute value of the insulating film 11 is 3 kV or more (S1), and generating a corona discharge between the grounded needle-shaped conductor 30 and the charged insulating film 11 (S2).

In the static charge elimination method of the present embodiment and its modification, the insulating film 11 is charged by bringing the charger 20 into contact with a surface (at least one of the first surface 12 and the second surface 13) of the insulating film 11 such that the absolute value of the insulating film 11 is 3 kV or more. Therefore, it is possible to reliably generate a corona discharge between the grounded needle-shaped conductor 30 and the insulating film 11. According to the static charge elimination method of the present embodiment and its modification, the static charges on the insulating film 11 can be reliably eliminated.

In the static charge elimination method of the present embodiment and its modification, the corona discharge is generated between the grounded needle-shaped conductor 30 and the charged insulating film 11. The grounded needle-shaped conductor 30 constitutes a self-discharge type static charge eliminator. In the static charge elimination method of the present embodiment and its modification, it is not necessary to apply a high voltage to the needle-shaped conductor 30 so as to generate a corona discharge between the needle-shaped conductor 30 and the insulating film 11. Therefore, the static charge elimination method of the present embodiment and its modification may be used in a work environment (for example, a process of manufacturing a coil which includes a step of covering a conductor with the insulating film 11) which is required to prevent sparks from occurring.

In the static charge elimination method of the present embodiment and its modification, charging the insulating film 11 includes bringing the insulating member 21a, 22a, 23a having a different level in the triboelectric series from the insulating film 11 into contact with a surface (at least one of the first surface 12 and the second surface 13) of the insulating film 11. According to the static charge elimination method of the present embodiment and its modification, the insulating film 11 may be charged to such an extent that a corona discharge may be reliably generated between the grounded needle-shaped conductor 30 and the insulating film 11 simply by bringing the insulating member 21a, 22a, 23a into contact with a surface (at least one of the first surface 12 and the second surface 13) of the insulating film 11.

Second Embodiment

A static charge eliminator 2 according to a second embodiment will be described with reference to FIG. 6. The static charge eliminator 2 of the present embodiment has substantially the same configuration as the static charge eliminator 1 of the first embodiment except the following points.

In the static charge eliminator 2 of the present embodiment, one or more charging units (21, 22) are a plurality of charging units (21, 22). At least one of the plurality of charging units (21, 22) is configured to be switchable between a first state (indicated by a solid line in FIG. 6) in which the at least one of the plurality of charging units (21, 22) charges the insulating film 11 and a second state (indicated by a two-dot chain line in FIG. 6) in which the at least one of the plurality of charging units (21, 22) imparts no static charge to the insulating film 11. Specifically, in the first state, the insulating members 21a, 22a are brought into contact with the insulating film 11, and in the second state, the insulating members 21a, 22a are separated from the insulating film 11. In the second state, both the contact pressure and the contact length between the insulating member 21a, 22a and the insulating film 11 are zero.

Specifically, at least one of the plurality of charging units (21, 22) is connected to a drive unit (41, 42). The drive unit (41, 42) is configured to move at least one of the plurality of charging units (21, 22) in a direction crossing a surface (at least one of the first surface 12 and the second surface 13) of the insulating film 11. More specifically, the first drive unit 41 is connected to the first charging unit 21, more specifically to the roller 21b. The first drive unit 41 is configured to move the first charging unit 21, more specifically the roller 21b in a direction crossing a surface (at least one of the first surface 12 and the second surface 13) of the insulating film 11. The second drive unit 42 is connected to the second charging unit 22, more specifically to the roller 22b. The second drive unit 42 is configured to move the second charging unit 22, more specifically the roller 22b in a direction crossing a surface (at least one of the first surface 12 and the second surface 13) of the insulating film 11.

The first drive unit 41 is configured to move the first charging unit 21 in a direction crossing a surface (at least one of the first surface 12 and the second surface 13) of the insulating film 11. Specifically, the first drive unit 41 may be configured to move the roller 21b in a direction orthogonal to the first surface 12 of the insulating film 11. The insulating member 21a covered on the roller 21b may be movable in a direction crossing a surface (at least one of the first surface 12 and the second surface 13) of the insulating film 11. Specifically, the insulating member 21a covered on the roller 21b may be movable in a direction orthogonal to the first surface 12 of the insulating film 11.

The second drive unit 42 is configured to move the second charging unit 22 in a direction crossing a surface (at least one of the first surface 12 and the second surface 13) of the insulating film 11. Specifically, the second drive unit 42 may be configured to move the roller 22b in a direction orthogonal to the second surface 13 of the insulating film 11. The insulating member 22a covered on the roller 22b may be movable in a direction crossing a surface (at least one of the first surface 12 and the second surface 13) of the insulating film 11. Specifically, the insulating member 22a covered on the roller 22b may be movable in a direction orthogonal to the second surface 13 of the insulating film 11.

According to the static charge eliminator 2 of the present embodiment, the insulating film 11 may be charged such that the absolute value of the surface potential of the insulating film 11 is surely 3 kV or more. For example, when only one charging unit (for example, the first charging unit 21) is used to charge the insulating film 11, it may be difficult to charge the insulating film 11 such that the absolute value of the surface potential of the insulating film 11 is 3 kV or more. In this case, the drive unit (for example, the second drive unit 42) is used to bring the other charging unit (for example, the second charging unit 22) into contact with the insulating film 11 so as to switch the charging unit 22 to the first state in which charging unit 22 charges the insulating film 11. Thus, the insulating film 11 is charged by the one charging unit (for example, the first charging unit 21) and the other charging unit (for example, the second charging unit 22). Specifically, the insulating film 11 is contacted by the one insulating member (for example, the insulating member 21a) and the other insulating member (for example, the insulating member 22a). Thus, according to the static charge eliminator 2, the insulating film 11 may be charged such that the absolute value of the surface potential of the insulating film 11 is surely 3 kV or more. Therefore, it is possible to use the static charge eliminator 2 to reliably eliminate the static charges on the insulating film 11.

11

According to the static charge eliminator 2 of the present embodiment, the insulating film 11 may be charged such that the absolute value of the surface potential of the insulating film 11 is surely 30 kV or less. For example, when all of the charging units (for example, the first charging unit 21 and the second charging unit 22) are used to charge the insulating film 11, the absolute value of the surface potential of the insulating film 11 may exceed 30 kV. In this case, a drive unit (for example, the second drive unit 42) is used to move at least one charging unit (for example, the second charging unit 22) away from the insulating film 11 so as to switch the second charging unit 22 to the second state in which the second charging unit 22 imparts no static charge to the insulating film 11. Thus, the insulating film 11 is charged only by one charging unit (for example, the first charging unit 21). Specifically, only one insulating member (for example, the insulating member 21a) is brought into contact with the insulating film 11. Thus, according to the static charge eliminator 2, the insulating film 11 may be charged such that the absolute value of the surface potential of the insulating film 11 is surely 30 kV or less, whereby it is possible to prevent the insulating film 11 from being imparted with excessive static charges by the charger 20. Therefore, the static charges imparted to the insulating film 11 by the charger 20 may be eliminated in a short time by the grounded needle-shaped conductor 30.

The insulating member (for example, the insulating member 21a) included in one or more (for example, the first charging unit 21) of the plurality of charging units (21, 22) may be made of a different material from the insulating member (for example, the insulating member 22a) included in the rest (for example, the second charging unit 22) of the plurality of charging units (21, 22).

According to the static charge eliminator 2 of the present embodiment, the insulating film 11 may be charged such that the absolute value of the surface potential of the insulating film 11 is surely 3 kV or more and 30 kV or less. For example, when one charging unit (for example, the first charging unit 21) is used to charge the insulating film 11, it may be difficult to charge the insulating film 11 such that the absolute value of the surface potential of the insulating film 11 is 3 kV or more and 30 kV or less. In this case, the other charging unit (for example, the second charging unit 22) is used to charge the insulating film 11 in place of the one charging unit (for example, the first charging unit 21). Specifically, a drive unit (for example, the first drive unit 41) is used to move one charging unit (for example, the first charging unit 21) away from the insulating film 11 so as to switch the first charging unit 21 to the second state in which the first charging unit 21 imparts no static charge to the insulating film 11, and meanwhile, another drive unit (for example, the second drive unit 42) is used to bring the other charging unit (for example, the second charging unit 22) into contact with the insulating film 11 so as to switch the second charging unit 22 to the first state in which the second charging unit 22 imparts no static charge to the insulating film 11. Thereby, the insulating film 11 is charged by using the other charging unit (for example, the second charging unit 22) in place of the one charging unit (for example, the first charging unit 21). Specifically, instead of one insulating member (for example, the insulating member 21a), the insulating film 11 is contacted by the other insulating member (for example, the insulating member 22a) which is made of a material different from the one insulating member. Thus, according to the static charge eliminator 2, the insulating film 11 may be charged such that the absolute value of the surface potential of the insulating film 11 is surely 3 kV or more and 30 kV

12

or less. Therefore, it is possible for the static charge eliminator 2 to reliably eliminate the static charges on the insulating film 11 in a short time.

In addition to the effects of the static charge eliminator 1 of the first embodiment, the static charge eliminator 2 of the present embodiment provide the following effects.

In the static charge eliminator 2 of the present embodiment, one or more charging units (21, 22) are a plurality of charging units (21, 22). At least one of the plurality of charging units (21, 22) is configured to be switchable between a first state in which the at least one of the plurality of charging units (21, 22) charges the insulating film 11 and a second state in which the at least one of the plurality of charging units (21, 22) imparts no static charge to the insulating film 11. According to the static charge eliminator 2 of the present embodiment, the static charges on the insulating film 11 can be reliably eliminated.

In the static charge eliminator 2 of the present embodiment, the insulating members 21a, 22a may be configured to be movable in a direction crossing a surface (at least one of the first surface 12 and second surface 13) of the insulating film 11. Therefore, the insulating film 11 may be charged while being conveyed. According to the static charge eliminator 2 of the present embodiment, the static charges on the insulating film 11 can be reliably eliminated in a short time.

In the static charge eliminator 2 of the present embodiment, the insulating member (for example, the insulating member 21a) included in one or more (for example, the first charging unit 21) of the plurality of charging units (21, 22) may be made of a different material from the insulating member (for example, the insulating member 22a) included in the rest (for example, the second charging unit 22) of the plurality of charging units (21, 22). According to the static charge eliminator 2 of the present embodiment, the static charges on the insulating film 11 can be reliably eliminated in a short time.

Third Embodiment

A static charge eliminator 3 and a static charge elimination method according to a third embodiment will be described with reference to FIGS. 7 and 8. The static charge eliminator 3 of the present embodiment has substantially the same configuration as the charge removing device 1 of the first embodiment and the static charge elimination method of the present embodiment includes substantially the same steps as the static charge elimination method of the first embodiment except the following points.

In the static charge eliminator 3 of the present embodiment, at least one of the one or more charging units (21, 22) is configured such that at least one of a contact pressure and a contact length between the insulating member 21a, 22a and the insulating film 11 is changed. In the static charge elimination method of the present embodiment, charging the insulating film 11 includes changing at least one of the contact pressure and the contact length between the insulating member 21a, 22a and the insulating film 11.

At least one of the one or more charging units (21, 22) is connected to a drive unit (41, 42). The drive unit (41, 42) is configured to move at least one of the one or more charging units (21, 22) in a direction crossing a surface (at least one of the first surface 12 and the second surface 13) of the insulating film 11. The first charging unit 21, specifically the roller 21b is connected to the first drive unit 41, and the second charging unit 22, specifically the roller 22b is connected to the second drive unit 42.

The first drive unit **41** is configured to move the first charging unit **21** in a direction crossing a surface (at least one of the first surface **12** and the second surface **13**) of the insulating film **11**. Specifically, the first drive unit **41** may be configured to move the roller **21b** in a direction orthogonal to the first surface **12** of the insulating film **11**. The insulating member **21a** covered on the roller **21b** may be movable in a direction crossing a surface (at least one of the first surface **12** and the second surface **13**) of the insulating film **11**. Specifically, the insulating member **21a** covered on the roller **21b** may be movable in a direction orthogonal to the first surface **12** of the insulating film **11**.

The second drive unit **42** is configured to move the second charging unit **22** in a direction crossing a surface (at least one of the first surface **12** and the second surface **13**) of the insulating film **11**. Specifically, the second drive unit **42** may be configured to move the roller **22b** in a direction orthogonal to the second surface **13** of the insulating film **11**. The insulating member **22a** covered on the roller **22b** may be movable in a direction crossing a surface (at least one of the first surface **12** and the second surface **13**) of the insulating film **11**. Specifically, the insulating member **22a** covered on the roller **22b** may be movable in a direction orthogonal to the second surface **13** of the insulating film **11**.

The drive unit (for example, the first drive unit **41**) may be configured to move at least one (for example, the first charging unit **21**) of the one or more charging units (**21, 22**) so that at least one (for example, the first charging unit **21**) of the one or more charging units (**21, 22**) presses the insulating film **11** in a first direction crossing the conveying direction of the insulating film **11**. The drive unit (for example, the second drive unit **42**) may be configured to move at least one (for example, the second charging unit **22**) of the one or more charging units (**21, 22**) so that at least one (for example, the second charging unit **22**) of the one or more charging units (**21, 22**) presses the insulating film **11** in a second direction which is opposite to the first direction and crossing the conveying direction of the insulating film **11**. At least one of the contact pressure and the contact length between the insulating member **21a, 22a** included in one or more charging units (**21, 22**) and the insulating film **11** may be changed by changing the moving distance of one or more charging units (**21, 22**).

According to the static charge eliminator **3** of the present embodiment, the insulating film **11** may be charged such that the absolute value of the surface potential of the insulating film **11** is surely 3 kV or more. For example, in the case of increasing the amount of static charges imparted to the insulating film **11** by the charger **20**, at least one of the one or more charging units (**21, 22**) may be moved so as to increase at least one of the contact pressure and the contact length between the insulating member **21a, 22a** included in one or more charging units (**21, 22**) and the insulating film **11**. Thus, according to the static charge eliminator **3**, the insulating film **11** may be charged such that the absolute value of the surface potential of the insulating film **11** is surely 3 kV or more. Therefore, the static charges on the insulating film **11** may be reliably eliminated by the grounded needle-shaped conductor **30**.

According to the static charge eliminator **3** of the present embodiment, the insulating film **11** may be charged such that the absolute value of the surface potential of the insulating film **11** is surely 30 kV or less. For example, in the case of decreasing the amount of static charges imparted to the insulating film **11** by the charger **20**, at least one of the one or more charging units (**21, 22**) may be moved so as to decrease at least one of the contact pressure and the contact

length between the insulating member **21a, 22a** included in one or more charging units (**21, 22**) and the insulating film **11**. Therefore, it is possible to prevent the insulating film **11** from being imparted with excessive static charges by the charger **20**. According to the static charge eliminator **3**, the insulating film **11** may be charged such that the absolute value of the surface potential of the insulating film **11** is surely 30 kV or less. Therefore, the static charges imparted to the insulating film **11** by the charger **20** may be eliminated in a short time by the grounded needle-shaped conductor **30**.

In the static charge eliminator **3** of the present embodiment, the insulating member (for example, the insulating member **21a**) included in one or more (for example, the first charging unit **21**) of the plurality of charging units (**21, 22**) may be made of a different material from the insulating member (for example, the insulating member **22a**) included in the rest (for example, the second charging unit **22**) of the plurality of charging units (**21, 22**). According to the static charge eliminator **3** of the present embodiment, even though both surfaces (the first surface **12** and the second surface **13**) of the insulating film **11** are made of different materials from each other, the insulating film **11** may be charged such that the absolute value of the surface potential of the insulating film **11** is surely 3 kV or more and 30 kV or less.

For example, the first surface **12** of the insulating film **11** may be charged by bringing the insulating member (for example, the insulating member **21a**) included in one or more (for example, the first charging unit **21**) of the plurality of charging units (**21, 22**) into contact with the first surface **12** of the insulating film **11**, and the second surface **13** of the insulating film **11** may be charged by bringing the insulating member (for example, the insulating member **22a**) included in the rest (for example, the second charging unit **22**) of the plurality of charging units (**21, 22**) into contact with the second surface **13** of the insulating film **11**. The insulating member (for example, the insulating member **21a**) included in one or more (for example, the first charging unit **21**) of the plurality of charging units (**21, 22**) is made of a different material from the insulating member (for example, the insulating member **22a**) included in the rest (for example, the second charging unit **22**) of the plurality of charging units (**21, 22**). Therefore, according to the static charge eliminator **3**, even though both surfaces (the first surface **12** and the second surface **13**) of the insulating film **11** are made of different materials from each other, the insulating film **11** may be charged such that the absolute value of the surface potential of the insulating film **11** is surely 3 kV or more and 30 kV or less. Therefore, it is possible for the static charge eliminator **3** to reliably eliminate the static charges on the insulating film **11** in a short time.

With reference to FIGS. 7 and 8, the static charge eliminator **3** of the present embodiment further includes a third drive unit **43** and a controller **45**. The third drive unit **43** is configured to move the needle-shaped conductor **30** in a direction crossing a surface (at least one of the first surface **12** and the second surface **13**) of the insulating film **11**. Specifically, the third drive unit **43** may be configured to move the needle-shaped conductor **30** in a direction orthogonal to the first surface **12** of the insulating film **11**. The controller **45** is configured to maintain a gap **g** between the needle-shaped conductor **30** and the insulating film **11**. Specifically, the controller **45** may control the third drive unit **43** so as to maintain the gap **g** between the needle-shaped conductor **30** and the insulating film **11**.

In the static charge elimination method of the present embodiment, generating a corona discharge including controlling the position of the needle-shaped conductor **30**

relative to the insulating film 11 so as to maintain the gap g between the needle-shaped conductor 30 and the insulating film 11. Since the gap g between the needle-shaped conductor 30 and the insulating film 11 is maintained by the control section 45, it is possible for the grounded needle-shaped conductor 30 to stably and reliably eliminate the static charges on the insulating film 11.

The controller 45 may be further connected to a drive unit (for example, the first drive unit 41, the second drive unit 42) configured to move one or more charging units (21, 22). The gap g between the needle-shaped conductor 30 and the insulating film 11 may change along with the moving distance of one or more charging units (21, 22) by the drive unit (for example, the first drive unit 41, the second drive unit 42). Thus, the controller 45 moves the needle-shaped conductor 30 so as to compensate for the change in the gap g. In this way, the controller 45 can maintain the gap g between the needle-shaped conductor 30 and the insulating film 11.

In addition to the effects of the static charge eliminator 1 of the first embodiment, the static charge eliminator 3 of the present embodiment provide the following effects.

In the static charge eliminator 3 of the present embodiment, at least one of the one or more charging units (21, 22) is configured such that at least one of the contact pressure and the contact length between the insulating member 21a, 22a and the insulating film 11 is changed. According to the static charge eliminator 3 of the present embodiment, the static charges on the insulating film 11 can be reliably eliminated.

In the static charge eliminator 3 of the present embodiment, the insulating members 21a and 22a are configured to be movable in a direction crossing a surface (at least one of the first surface 12 and the second surface 13) of the insulating film 11. Therefore, the insulating film 11 may be charged while being conveyed. According to the static charge eliminator 3 of the present embodiment, the static charges on the insulating film 11 can be reliably eliminated in a short time.

In the static charge eliminator 3 of the present embodiment, the insulating member (for example, the insulating member 21a) included in one or more (for example, the first charging unit 21) of the plurality of charging units (21, 22) may be made of a different material from the insulating member (for example, the insulating member 22a) included in the rest (for example, the second charging unit 22) of the plurality of charging units (21, 22). Therefore, even though both surfaces (the first surface 12 and the second surface 13) of the insulating film 11 are made of different materials from each other, the insulating film 11 may be charged such that the absolute value of the surface potential of the insulating film 11 is surely 3 kV or more.

The static charge eliminator 3 of the present embodiment may further include a controller 45. The controller 45 may be configured to maintain the gap g between the needle-shaped conductor 30 and the insulating film 11. According to the static charge eliminator 3 of the present embodiment, it is possible for the grounded needle-shaped conductor 30 to stably and reliably eliminate the static charges on the insulating film 11.

In the static charge elimination method of the present embodiment, charging the insulating film 11 includes changing at least one of the contact pressure and the contact length between the insulating member 21a, 22a and the insulating film 11. According to the static charge elimination method of the present embodiment, the static charges on the insulating film 11 can be reliably eliminated.

In the static charge elimination method of the present embodiment, generating a corona discharge including controlling the position of the needle-shaped conductor 30 relative to the insulating film 11 so as to maintain the gap g between the needle-shaped conductor 30 and the insulating film 11. According to the static charge elimination method of the present embodiment, it is possible for the grounded needle-shaped conductor 30 to stably and reliably eliminate the static charges on the insulating film 11.

Fourth Embodiment

A static charge eliminator 4 according to a fourth embodiment will be described with reference to FIG. 9. The static charge eliminator 4 of the present embodiment has substantially the same configuration as the static charge eliminator 1 of the first embodiment except the following points.

The static charge eliminator 4 of the present embodiment further includes a conductive case 50 containing the charger 20 and the needle-shaped conductors 30. The conductive case 50 is not particularly limited, it may be made of a conductive metal such as aluminum, stainless steel or iron, or an conductive resin sheet subjected to an antistatic treatment.

The conductive case 50 is configured to confine therein ions generated by the corona discharge between the needle-shaped conductor 30 and the insulating film 11. The ions generated by the corona discharge between the needle-shaped conductor 30 and the insulating film 11 may be used to reliably eliminate the static charges on the insulating film 11.

The conductive case 50 may be grounded. When the insulating film 11 is unwound from the bobbin 10, the insulating film 11 is peeled off from the adjacent insulating film 11 or rubs against the adjacent insulating film 11. Thereby, the insulating film 11 is charged. When the insulating members 21a and 22a are brought into contact with the insulating film 11, the insulating members 21a and 22a are charged accordingly. The grounded conductive case 50 can prevent foreign matters such as dust from being adhered to the charged insulating film 11 and the charged insulating members 21a, 22a.

In addition to the effects of the static charge eliminator 1 of the first embodiment, the static charge eliminator 4 of the present embodiment provide the following effects.

The static charge eliminator 4 of the present embodiment further includes a conductive case 50 containing the charger 20 and the needle-shaped conductors 30. The conductive case 50 confines the ions generated by the corona discharge between the needle-shaped conductor 30 and the insulating film 11. According to the static charge eliminator 4 of the present embodiment, the static charges on the insulating film 11 may be reliably eliminated in a short time.

Fifth Embodiment

A static charge eliminator 5 according to a fifth embodiment will be described with reference to FIG. 10. The static charge eliminator 5 of the present embodiment has substantially the same configuration as the static charge eliminator 1 of the first embodiment except the following points.

In the static charge eliminator 5 of the present embodiment, the plurality of charging units (the first charging unit 21 and the second charging unit 22) are configured to sandwich the insulating film 11 with the plurality of rollers 21b and 22b covered respectively by the insulating members 21a and 22a. The insulating film 11 is sandwiched between

the insulating member 21a and the insulating member 22a. Specifically, the static charge eliminator 5 may further include pressing members 55 and 56. The pressing member 55 is configured to press the first charging unit 21 against the insulating film 11, and the pressing member 56 is configured to press the second charging unit 22 against the insulating film 11. The pressing members 55 and 56 each may be, for example, a biasing member such as a spring or a pressing machine.

In the static charge elimination method of the present embodiment, charging the insulating film 11 includes bringing the insulating members 21a, 22a into contact with the surfaces (the first surface 12 and the second surface 13) of the insulating film 11 by sandwiching the insulating film 11 with a plurality of rollers 21b, 22b covered respectively by the insulating members 21a, 22a. Specifically, the pressing member 55 presses the first charging unit 21 against the insulating film 11, and the pressing member 56 presses the second charging unit 22 against the insulating film 11. In this way, the insulating film 11 may be sandwiched by the plurality of rollers 21b, 22b covered respectively by the insulating members 21a, 22a. The insulating film 11 may be sandwiched between the insulating member 21a and the insulating member 22a.

In addition to the effects of the static charge eliminator 1 and the static charge elimination method of the first embodiment, the static charge eliminator 5 and the static charge elimination method of the present embodiment provide the following effects.

In the static charge eliminator 5 of the present embodiment, the plurality of charging units (the first charging unit 21 and the second charging unit 22) are configured to sandwich the insulating film 11 with the plurality of rollers 21b and 22b covered respectively by the insulating members 21a and 22a. Therefore, even though wrinkles are present on the insulating film 11, the insulating members 21a and 22a may be ensured to contact all the surfaces (the first surface 12 and the second surface 13) of the insulating film 11. According to the static charge eliminator 5 of the present embodiment, the surfaces (the first surface 12 and the second surface 13) of the insulating film 11 may be charged such that the absolute value of the surface potential of each surface (the first surface 12, the second surface 13) of the insulating film 11 is surely 3 kV.

In the static charge elimination method of the present embodiment, the charger 20 (the first charging unit 21, the second charging unit 22) includes a plurality of rollers 21b, 22b covered respectively by the insulating members 21a, 22a. Charging the insulating film 11 includes bringing the insulating members 21a, 22a into contact with the surfaces (the first surface 12 and the second surface 13) of the insulating film 11 by sandwiching the insulating film 11 with a plurality of rollers 21b, 22b covered respectively by the insulating members 21a, 22a. Therefore, even though wrinkles are present on the insulating film 11, the insulating members 21a and 22a may be ensured to contact all the surfaces (the first surface 12 and the second surface 13) of the insulating film 11. According to the static charge elimination method of the present embodiment, the surfaces (the first surface 12 and the second surface 13) of the insulating film 11 may be charged such that the absolute value of the surface potential of each surface (the first surface 12, the second surface 13) of the insulating film 11 is surely 3 kV.

The first to fifth embodiments and the modification of the first embodiment disclosed herein are merely examples in all aspects and not limited thereto. At least two of the first to fifth embodiments disclosed herein may be carried out in

any combined appropriately as long as they are not contradictory to each other. For example, the static charge eliminator 1, 1b, 2, 4, 5 of the first, second, fourth, fifth embodiment and the modification of the first embodiment may include the controller 45 described in the third embodiment and configured to maintain the gap g between the needle-shaped conductor 30 and the insulating film 11. The static charge eliminator 1, 1b, 2, 3, 5 of the first, second, third, fifth embodiment and the modification of the first embodiment may include the conductive case 50 described in the fourth embodiment. The scope of the present invention is defined by the terms of the claims, rather than the description above, and is intended to include any modifications within the meaning and scope equivalent to the terms of the claims.

REFERENCE SIGNS LIST

1, 1b, 2, 3, 4, 5: static charge eliminator; 10: bobbin; 11: insulating film; 12: first surface; 13: second surface; 20: charger; 21: first charging unit; 21a, 22a, 23a: insulating member; 21b, 22b, 23b: roller; 22: second charging unit; 23: third charging unit; 30: needle-shaped conductor; 31: tip; 41: first drive unit; 42: second drive unit; 43: third drive unit; 45: controller; 50: conductive case; 55, 56: pressing member

The invention claimed is:

1. A static charge eliminator comprising:
a charger including one or more charging units; and
a grounded needle-shaped conductor, wherein
the charger being configured to charge an insulating film
by contacting the insulating film such that an absolute
value of a surface potential of the insulating film is 3
kV or more,
each of the one or more charging units includes a roller
covered by an insulating member having a different
level in a triboelectric series from the insulating film,
the insulating member is configured to contact a surface
of the insulating film, and
a needle-shaped conductor is arranged to generate a
corona discharge between the insulating film charged
by the charger and the needle-shaped conductor.
2. The static charge eliminator according to claim 1,
wherein
the one or more charging units are a plurality of the
charging units.
3. The static charge eliminator according to claim 2,
wherein
the surface of the insulating film includes one surface of
the insulating film and the other surface thereof oppo-
site to the one surface,
at least one of the plurality of charging units is configured
to face the one surface, and
the rest of the plurality of charging units is configured to
face the other surface.
4. The static charge eliminator according to claim 3,
wherein
the insulating member included in the at least one of the
plurality of charging units is made of a different mate-
rial from the insulating member included in the rest of
the plurality of charging units.
5. The static charge eliminator according to claim 2,
wherein
at least one of the plurality of charging units is configured
to be switchable between a first state in which the at
least one of the plurality of charging units charges the
insulating film and a second state in which the at least

19

- one of the plurality of charging units imparts no static charge to the insulating film.
6. The static charge eliminator according to claim 2, wherein at least one of the plurality of charging units is configured such that at least one of a contact pressure and a contact length between the insulating member and the insulating film is changed.
7. The static charge eliminator according to claim 5, wherein the insulating member is configured to be movable in a direction crossing the surface of the insulating film.
8. The static charge eliminator according to claim 5, wherein the insulating member included in the at least one of the plurality of charging units is made of a different material from the insulating member included in the rest of the plurality of charging units.
9. The static charge eliminator according to claim 2, wherein the plurality of charging units are configured to sandwich the insulating film with a plurality of the rollers each covered by the insulating member.
10. The static charge eliminator according to claim 1, further comprising a conductive case containing the charger and the needle-shaped conductor.
11. A static charge elimination method comprising: charging an insulating film by bringing a charger into contact with a surface of the insulating film such that an absolute value of a surface potential of the insulating film is 3 kV or more; and

20

- generating a corona discharge between a grounded needle-shaped conductor and the charged insulating film, wherein the charging the insulating film includes bringing a roller covered by an insulating member having a different level in a triboelectric series from the insulating film into contact with the surface of the insulating film.
12. The static charge elimination method according to claim 11, wherein the charging the insulating film includes changing at least one of a contact pressure and a contact length between the insulating member and the insulating film.
13. The static charge elimination method according to claim 11, wherein the charger includes a plurality of the rollers each covered by the insulating member, and the charging the insulating film includes bringing the insulating member into contact with the surface of the insulating film by sandwiching the insulating film with the plurality of rollers each covered by the insulating member.
14. The static charge elimination method according to claim 11, wherein the generating the corona discharge includes controlling the position of the needle-shaped conductor relative to the insulating film so as to maintain a gap between the needle-shaped conductor and the insulating film.
